UNITED STATES PATENT OFFICE.

GEORGE I. ROCKWOOD, OF WORCESTER, MASSACHUSETTS.

FUSIBLE LINK.

No. 911,162.

Specification of Letters Patent

Patented Feb. 2, 1909.

Application filed September 22, 1908. Serial No. 454,159.

To all whom it may concern:

Be it known that I, GEORGE I. ROCKWOOD, a citizen of the United States, residing at Worcester, in the county of Worcester and 5 Commonwealth of Massachusetts, have invented a new and useful Improvement in a Fusible Link, of which the following is a specification, accompanied by drawings forming a part of the same, in which—

10 Figure 1 denotes a top view of my improved fusible link. Fig. 2 is a side view shown in central section, and Fig. 3 is a transverse sectional view on the plane of the broken line 3—3, Figs. 1 and 2.

15 Similar reference letters and figures refer to similar parts in the different views.

The object of my present invention is to provide a fusible link adapted to form a constituent part of a tensile support such, for 20 example, as that employed in holding up fire proof doors or shutters between the different departments of stores or warehouses, said fusible link being designed to yield at a predetermined degree of heat and allow the 25 door or shutter to fall.

Appliances for fire protection of the kind referred to have been heretofore employed provided with a tensile support having a yielding link, comprising two members 30 soldered together by a material fusible at a determinate degree of heat. In links of this character, however, the adhesive force is exerted at right angles to the line of tensile strain, so that the power required to separate 35 the members is determined by the adhesion of one to the other and this, in certain cases, may yield before the soldering material has become entirely fused by heat.

In my improved fusible link I provide the 40 two contacting members with abutting surfaces placed at an oblique angle to the line of tensile strain, and I hold these surfaces in contact by surrounding them with an inclosing shell, which is filled with a material 45 fusible at a predetermined degree of heat. When a tensile strain is applied to the two members of the link, the oblique abutting surfaces tend to separate the members and cause a compression of the fusible material, 50 which is, however, sufficient to resist the tensile strain applied until it has become softened by heat. The contact of the oblique surfaces of the two members of the link is, therefore, determined by the compressibility of the fusible material contained in 55 the inclosing shell or case.

Referring to the accompanying drawings, 1 denotes a plate having on one end an extension 2, provided with an eye 3 to receive a hook or the eye of a cable 4. The plate 1 is provided with a shell 5 inclosing a space 6, preferably rectangular in cross section, and adapted to receive a mass of fusible metal 7. The central portion of the plate 1 is bent inward at a sharp angle providing an oblique 65 surface 8. In the formation of the link a plate 9 having an angular bend producing an oblique surface 10, fitting the oblique surface 8 on the plate 1, is inserted within the shell 5 in the position shown in central view in Fig. 70 2. The remaining space within the shell 5 is then filled with the metal 7, fusible at a predetermined degree of heat.

Any tensile strain applied to the two members 1 and 9 will be resisted by the 75 oblique surfaces 8 and 10 so long as the latter are held in contact by the incompressibility of the fusible material 7. When the fusible material 7, however, has become softened by heat and its compressibility decreased, the 80 oblique surface 8 will act as a cam surface and crowd the plate 9 into the mass of compressible metal 7 until the plate 9 slips by the tip 11, causing a separation in the link.

I claim,

85

1. A fusible link adapted to receive a tensile strain, comprising two members having contacting surfaces oblique to the line of tensile strain, and means for holding said oblique surfaces in contact, comprising a 90 mass of metal fusible at a predetermined degree of heat, in contact with the side of one of said members opposite to the other member, and non-fusible inclosing means attached to the other member in contact with 95 the outer side of said fusible material.

2. As an article of manufacture a fusible link comprising two members adapted to receive a tensile strain, and having contacting surfaces oblique to the line of tensile strain, 100 a shell or case attached to one of said members and inclosing the other member, with an intervening space to allow for the insertion or withdrawal of said inclosed member, and a material filling said intervening space, fusible at a predetermined degree of heat.

3. The within described fusible link, consisting of plates having interlocking oblique surfaces, an inclosing shell, and an inclosed metal fusible at a predetermined degree of 110 heat, by which said interlocked surfaces are held in contact.

4. In a fusible link, a plate having a V-shaped projection, a second plate having a corresponding V-shaped recess to receive said projection, and means for holding said plates in contact, comprising a metal fusible at a predetermined degree of heat and applied to one of said plates opposite to its con-
- tacting surface, and a shell attached to the other of said plates and inclosing said fusible metal.

GEORGE I. ROCKWOOD.
